UNITED STATES PATENT OFFICE.

JAMES A. ALLEN, OF PHILADELPHIA, PENNSYLVANIA.

BRANDING-TOOL.

SPECIFICATION forming part of Letters Patent No. 286,366, dated October 9, 1883.

Application filed October 14, 1882. (No model.)

To all whom it may concern:

Be it known that I, JAMES A. ALLEN, a citizen of the United States, and a resident of Philadelphia, Pennsylvania, have invented 5 certain Improvements in Branding-Tools, of which the following is a specification.

The main object of my invention is to so construct a branding-tool that the iron can be laid upon the fire face upward, a further object being to permit the iron to be readily applied to or detached from the handle, whereby one handle can be used for a number of irons.

In the accompanying drawings, Figure 1 is 15 a perspective view of a branding-tool made in accordance with my invention; Fig. 2, the same with the iron detached from the handle; Fig. 3, a side view, partly in section; Fig. 4, a sectional plan on the line 1 2, Fig. 3; and 20 Figs. 5, 6, 7, and 8, views of modified forms of the tool.

By constructing the tool in accordance with my invention the iron can be laid upon the fire face upward, and a number of irons can 25 be used with each handle, the operation of branding being facilitated, as one iron can be heated while another is in use.

In the tool shown in Figs. 1, 2, 3, and 4 the handle consists of a tubular stem, *a*, having a forked lower end, and a rod, *b*, adapted to said tubular stem, and also having a forked lower end, both the stem *a* and rod *b* having suitable projections, by which they can be firmly grasped. The arms *d* of 35 the handle are hooked at the lower ends for adaptation to pins *e*, which extend across recesses *f* in the back of the iron *B*, and the lower ends of the arms *g* of the rod *b* are adapted to bear upon inclined lugs *h* on the 40 back of the iron, these lugs bearing the relation to the recesses *f* shown in Fig. 4. In fitting the handle to the iron the parts are adjusted to the position shown in Fig. 2, the arms *g* of the rod *b* being in line with the arms 45 *d* of the handle. The hooked ends of the arms *d* are then applied to the pins *e*, and the rod *b* turned so as to bring the arms *g* of the same to a position at right angles, or thereabout, to the arms *d*, the lower ends of said arms *g* 50 bearing upon the inclined lugs *h*, and serv-

ing to lock the handle to the iron by preventing the swinging of the same on the arms, or the disengagement of the said arms from the pins *e*. The iron *B* is hung to the handle-arms some distance from the center of 55 the iron, and each of the arms *d* has a lug, *m*, which bears upon the back of the iron and prevents the preponderance of weight from causing the iron to swing on the arms *d* when released from the control of the locking-arms. 60

In Fig. 5 I have shown a modification of my invention, in which the hooked arms *d* are adapted to pins projecting from the edges of the iron, and a single locking-arm, *g*, only 65 is used.

The iron, when detached from the handle, can be laid on the fire face upward, so that there is no risk of destroying or impairing the face of the brand. Instead of detaching the iron, the locking-arms *g* may be turned 70 to the position shown in Fig. 2, in order to unlock the iron, and the handle can then be turned down against the back of the iron, so as to permit the same to be laid upon the fire face upward. The iron may also be pivoted to the 75 handle, so as not to be detachable from the same, if desired, instances of this form of the tool being shown in Figs. 6, 7, and 8. Fig. 6 shows a 80 forked handle so pivoted, and provided with a single locking-arm, while Fig. 7 shows a single handle-arm and a forked locking-arm. In Fig. 8 the locking-arm is of a somewhat 85 different character from that shown in the other figures, the arm in this case being pivoted to the handle so as to swing up, in order to unlock the iron, and being prevented from 90 swinging up accidentally by a pin, *x*, passed through the lugs to which the arm is hung, this pin being removed when it is desired to unlock the iron from the handle.

I claim as my invention—

1. The combination of a branding-iron with a pivoted handle and a locking-arm, all substantially as set forth.
2. The combination of a branding-iron, a locking-arm, and a handle pivoted to the iron, but detachable therefrom, as set forth.
3. The combination of a branding-iron, a handle pivoted thereto, and a locking-arm adapted to turn on the handle, as set forth.

4. The combination of a branding-iron, a handle pivoted thereto, and a pivoted locking-arm, adapted to engage with a lug or lugs on the iron, as set forth.
5. The combination of a branding-iron, a handle pivoted thereto, and having a lug or lugs, *m*, and a locking-arm, as set forth.

In testimony whereof I have signed my name to this specification in the presence of two subscribing witnesses.

JAS. A. ALLEN.
